(57) **CLAIM**

The ornamental design for a building surface covering, as shown and described.

DESCRIPTION

FIG. 1 is a top perspective view of a building surface covering of the present invention;

FIG. 2 is a bottom perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

The broken lines illustrating portions of the building surface covering form no part of the claimed design. The dot-dash lines define the bounds of the claimed design and form no part thereof.

1 Claim, 6 Drawing Sheets
